CHARLES M. MINOR, OF BRIDGEPORT, AND HENRY S. FROST, OF WATERTOWN, ASSIGNORS TO THEMSELVES, AUGUSTUS N. WOOLSON, AND ANTHONY G. DAVIS, OF WATERTOWN, CONNECTICUT.

Letters Patent No. 75,692, dated March 17, 1868.

IMPROVEMENT IN UMBRELLAS.

The Schedule referred to in these Letters Patent and making part of the same.

TO ALL WHOM IT MAY CONCERN:

Be it known that we, CHARLES M. MINOR, of Bridgeport, in the county of Fairfield, and State of Connecticut, and HENRY S. FROST, of Watertown, in the county of Litchfield, and State of Connecticut, have invented a new Improvement in Umbrellas; and we do hereby declare the following, when taken in connection with the accompanying drawings, and the letters of reference marked thereon; to be a full, clear, and exact description of the same, and which said drawings constitute part of this specification, and represent, in—

Figure 1, a side view, one of the bows and brace attached in the position as opened.

Figure 2, the same folded.

Figure 3, an upper side view of the same in an open position.

Figure 4, an upper side view closed; and in

Figure 5, a transverse section.

This invention relates to an improvement in that class of umbrellas which are constructed with jointed bows, so as to fold into a compact form; and consists, first, in constructing the one part of the bow so as to form a latch for the other part when open; and, second, in hinging the two parts of the bow and the brace to one and the same piece.

To enable others to construct our improvement, we will proceed to describe the same, as illustrated in the accompanying drawings.

a is the one part of the bow, *b* the other part, and *c* the brace. The part *a*, which we employ as the upper part, is formed from wire bent as denoted in fig. 3, so as to form a loop at the end, and the end turned around and united to the body of the wire at *d*, and the said loop is bent down as at *f*, figs. 1 and 2; then within the loop is cast or fixed solidly a block, *i*, extending down, so that the brace *c* may be pivoted thereto, as seen in figs. 1, 2, and 5, and into the said block *i* the other part, *b*, of the bow is pivoted, as seen in figs. 2 and 3, and so as to turn freely on its pivot from the position in fig. 1 to that in fig. 2. The loop at the point *p* is a little narrower than the diameter of the part *b*, as denoted in fig. 4, opening a little from that point toward the extremity of the loop, so that when the bow is turned down to the position in fig. 1, it is pressed down into the bow at the narrow point, and springs into the extreme end of the loop, and is there held by the narrower portion or point of the loop, but yet so that it may be easily turned up therefrom. Thus, when the umbrella is extended, and the user desires to fold the same, turn up the part *b* of the several bows, as denoted in figs. 2 and 4, and the umbrella is folded into nearly half its usual length. Thus we form a cheap and durable lock-joint for the bows.

Having thus fully described our invention, what we claim as new and useful, and desire to secure by Letters Patent, is—

1. The construction of the loop upon the end of one of the parts of the rib, so as to receive and lock or brace the other part therein, substantially as set forth.
2. The folding joint, consisting of the three parts *a*, *b*, and *c*, by means of the block *i*, two of the parts being jointed or pivoted, substantially as set forth.

C. M. MINOR,
H. S. FROST.
